MEANS FOR SEALING CONTAINERS

George J. Meyer, Milwaukee, Wis.

Application August 15, 1935, Serial No. 36,264

2 Claims. (Cl. 215—31)

The invention relates to containers and closures therefor, and to a method of applying the closures.

An object of the invention is to provide a container and closure of inexpensive construction capable of simple application to each other to form a tight seal, the closure being readily removable from the container by various simple implements.

Another object of the invention is to provide an improved method of applying a side-sealing sheet metal closure to a container.

The invention further consists in the several features hereinafter described and claimed.

In the accompanying drawing, illustrating an embodiment and method of the invention,

Fig. 1 is a sectional elevation showing a sealed bottle constructed in accordance with the invention;

Fig. 2 is an elevation of the bottle, the applied closure thereof being shown in section, and in readiness for a dishing operation to produce the configuration shown in Fig. 1;

Fig. 3 is a top view of the bottle, and

Fig. 4 is a detail sectional view of the bottle neck.

In the drawing, 10 designates a container which for purposes of illustration is shown to be a bottle. The neck portion 11 of the bottle is provided with an exterior conical sealing surface 12 converging upwardly, the sealing surface being slightly tapered, preferably in the ratio of approximately 1 in 16.

A plurality of shallow peripheral grooves 13 are formed around the neck of the bottle at the sealing surface to form serrations with downwardly facing shoulders 14, the purpose of the serrations being hereinafter explained. The sloping side wall of each peripheral groove is relatively steep and preferably terminates short of the downwardly facing shoulder of the next lower groove so as to leave an annular land around the bottle neck, as best seen in Figs. 2 and 4. The plane of each downwardly facing shoulder 14 extends substantially at right angles to the axis of the bottle neck and forms an abrupt angle with the tapered sealing surface of the neck.

A plurality of spaced radial projections 15 are formed on the neck portion 11 of the bottle and present ledges 16 for receiving a prying implement 17, as hereinafter described. The ledges 16 are preferably arranged helically, so that they will lie at different elevations. The lower edges 55 of the projections 15 preferably form cam sur-

faces 18. The projections 15 protect the conical sealing surface from chipping or other damage.

A closure is provided in the form of a cap 19 having a cover portion 20 and a downwardly projecting skirt 21, the skirt having substantially the same taper as the sealing surface 12 of the bottle. The cap is preferably made of sheet metal and is provided with a resilient liner or packing sheet 22 formed of paper, rubber or other suitable material, the liner being cemented or otherwise firmly attached in place. The lower edge of the cap skirt is provided with a rolled bead 23.

By means of a suitable simple tool or implement, not shown, the closure cap is pressed onto the bottle neck, the cap liner engaging the tapered sealing surface 12 of the bottle. The liner also engages the serrations 13, thereby considerably improving the hold or grip of the cap on the bottle neck, without injury to the liner. The skirt 21 of the cap, during application, slides readily over the steeply sloping side walls of the serration-forming grooves. During this operation the cover portion 20 of the cap is flat, as seen in Fig. 2. The pressing operation places the skirt 21 of the cap under peripheral tension, preferably without exceeding the elastic limit of the resilient sheet metal, and the resilient metal adapts itself to the varying diameter or slight variations in curvature of the sealing surface of the bottle. Even if the sealing surface 12 is damaged, it will still have ample area for a perfect seal. Thereafter the deformable cover portion 20 of the closure cap is preferably dished to a permanent set, as by means of a suitable pressing tool 24 seen in Fig. 2. The dishing of the closure cap to the final and permanent form shown in Fig. 1 increases the peripheral tension in the upper portion of the resilient cap skirt so as to substantially increase the holding pressure of the cap on the bottle neck.

The cap is retained in sealing engagement with the peripherally serrated bottle neck by the peripheral tension set up in the skirt of the resilient cap during the application of capping pressure. The fit of the closure cap on the bottle is sufficiently tight so that it can withstand considerable internal pressure in the bottle, such as may exist when the bottle contains a carbonated beverage. The abrupt shoulders 14 of the peripheral grooves 13 resist withdrawal of the cap and improve the sealing effect.

The bead 23 of the applied cap is spaced upwardly from the highest of the ledges 16 on the bottle neck, but the distance may vary because 55

of slight differences in the bottles and in the caps. The bead prevents excessive stretching at the edge of the skirt, so that this edge is approximately as resistant to stretch as other portions of the skirt. The liner 22 may be comparatively thin because of the resilience and deformability of the sheet metal cap.

5 To loosen or remove the cap, the prying implement 17, which may be a coin or other convenient object, is inserted between one of the ledges 16 and the lower edge of the cap, the ledge on which the implement is rested being selected according to the thickness of the implement. As the cap becomes loosened, the implement may be 10 shifted along the sloping ledge to obtain an optimum purchase. The shallow serrations 13 will not materially interfere with the removal of the cap.

15 What I claim as new and desire to secure by 20 Letters Patent is:

1. The combination, with a side sealing closure cap having a skirt with a resilient packing liner,

of a container having an exterior tapered sealing surface to receive said cap and having circumferential serration-forming grooves in said sealing surface, each groove presenting an abrupt downwardly facing shoulder at its upper edge 5 and a steeply sloping side wall extending to said sealing surface and forming the lower portion of said groove.

2. The combination, with a closure cap having a skirt, of a container having an exterior tapered sealing surface to tightly receive said cap thereon, said sealing surface having at an intermediate portion thereof a circumferential groove presenting an abrupt downwardly facing sharp-edged skirt-engaging shoulder at its upper edge 10 and a steeply sloping side wall extending to said sealing surface and forming the lower portion of said groove, whereby to offer greater resistance to the withdrawal of the cap than to the application of the cap.

20 GEORGE J. MEYER.
